UNITED STATES PATENT OFFICE.

EDWARD P. FUSSLER, OF BUFFALO, NEW YORK.

COMBINED FINISH MOLDING AND PRICE-CARD HOLDER FOR STORE SHELVES.

Application filed June 21, 1928. Serial No. 287,156.

This invention relates to a combined finish molding and price card holder for store shelves.

An important object of the invention is 5 to provide a construction such that a price card holder may be employed in conjunction with a shelf without in any manner detracting from the appearance thereof and may be so constructed that it is applied and forms 10 a part of the finish molding with which such shelves are ordinarily provided.

A further object of the invention is to provide a device of this character which may be very readily and cheaply manufactured 15 and which may be readily substituted for the moldings at present employed upon store shelves without any special operation other than that necessary to the removal of the old molding and the substitution of the new.

20 A still further object of the invention is to provide a device of this character which may be combined with any form of molding with which its use might be desired.

These and other objects I attain by the 25 construction shown in the accompanying drawing, wherein for the purpose of illustration is shown a preferred embodiment of my invention and wherein:—

Figure 1 is a front elevation of a shelf 30 having finish molding constructed in accordance with my invention applied thereto;

Figure 2 is an inner face view of the finish molding;

Figure 3 is a section on the line 3—3 of 35 Figure 1;

Figure 4 is a perspective view of the spring strip;

Figure 5 is an illustration of a modified molding and of an alternate position in which 40 the molding may be placed.

Referring now more particularly to the drawing, the numeral 10 indicates a store shelf and 11 a finish molding applied to the outer edge thereof. In accordance with 45 my invention, this molding is provided at its inner face with a rabbet 12 extending inwardly from one longitudinal edge thereof for a short distance. The inner face of the molding strip has attached thereto a 50 spring strip 13, preferably of spring bronze, brass or some similar material. This strip comprises a body portion 14 and a reverted flange 15, which diverges from the body portion and has a terminal edge 16 parallelling 55 the same. The width of the body portion is equal to the depth of the molding before the

formation of the rabbet therein and the flange 15 is of such length that its terminal portion 16 bears against the inner wall of the rabbet 12 with a pressure derived from 60 the resiliency of the material employed. Preferably, the edge of this terminal portion and the edge of the body portion are reverted, as indicated at 17 and 18 respectively, so that the strip is left with no raw edges 65 which may cause any damage.

In use of the device, the molding strip is secured to the shelf with the body portion 14 of the spring strip disposed inwardly. The rabbet 12 may be either upwardly or downwardly disposed and the cards or price tags, which are to be supported, are forced between the outer wall of the rabbet and the spring tongue formed by the flange 15 and its terminal portion 16. Since the terminal portion 16 flatly opposes the wall 12, a relatively broad grip upon the price card is provided, with the result that it may not be casually dislodged but when desired must be forcibly removed. This same disposal of the terminal 80 portion in parallel relation to the wall 12 and the reverting of the edge of this terminal portion insures against tearing of the card during its removal and the consequent collection within the slot or rabbet 12 of material 85 which, after a period of collection, would interfere with the proper action of the flange and with the insertion of other cards. When the channel 12 is downwardly disposed, as illustrated in Figure 5, all possibility of collection 90 of dust and dirt therein is eliminated and a very cleanly structure provided.

It will be obvious that by employing different forms of molding, as illustrated in the drawings, the molding of any of the present 95 store shelves may be readily matched, so that it can be replaced by molding having the card holding attachment. The construction illustrated provides a completely concealed card holding device and one which is so disposed 100 that it cannot come in contact with the clothing or persons of customers of self-service stores where apparatus of this character is most usually employed.

Since the construction hereinbefore set 105 forth is capable of a certain range of change and modification without materially departing from the spirit of the invention, I do not limit myself thereto except as hereinafter claimed.

I claim:—

1. In combination with a store shelf, a com-

bined finish molding and card holder secured to an exposed edge thereof, said molding and holder comprising a molding strip having a rabbet at and coextensive with its inner face which opens through one longitudinal edge thereof, and a spring metal strip coextensive with and secured to the inner face of the molding strip and having a reverted flange inclining inwardly toward the inner and side walls 10 of the rabbet.

2. In combination with a store shelf, a combined finish molding and card holder secured to an exposed edge thereof, said molding and holder comprising a molding strip having a rabbet at and coextensive with its inner face which opens through one longitudinal edge thereof and spring means within and coextensive with the rabbet for frictionally maintaining a card in position against the vertical face 20 of the rabbet.

3. In combination with a store shelf, a combined finish molding and card holder secured to an exposed edge thereof, said molding and holder comprising a molding strip having a rabbet at its inner face which opens through one longitudinal edge thereof, and a spring metal strip comprising a body portion secured to the inner face of the molding along one edge and having its opposite edge extended

30 into alignment with the longitudinal edge of the molding through which the rabbet opens, the last named edge having a reverted angularly disposed flange extending inwardly and downwardly toward the vertical face of the rabbet.

4. In combination with a store shelf, a combined finish molding and card holder secured to an exposed edge thereof, said molding and holder comprising a molding strip having a rabbet at its inner face which opens through 40 one longitudinal edge thereof, and a spring metal strip comprising a body portion secured to the inner face of the molding along one edge and having its opposite edge extended into alignment with the longitudinal edge of 45 the molding through which the rabbet opens, the last named edge having a reverted angularly disposed flange extending inwardly and downwardly toward the vertical face of the rabbet, the free edge of said flange having a 50 terminal paralleling the vertical wall of the rabbet and normally engaged therewith by the resiliency of the material from which the strip is formed.

55 In testimony whereof I hereunto affix my signature.

EDWARD P. FUSSLER.
